UNITED STATES PATENT OFFICE.

MICHAEL MULLARKEY, OF TORONTO, ONTARIO, CANADA.

REGISTERING BEVEL.

Application filed May 2, 1921. Serial No. 466,331.

To all whom it may concern:

Be it known that I, MICHAEL MULLARKEY, a citizen of the Dominion of Canada, residing at Toronto, in the county of York and Province of Ontario, Canada, have invented certain new and useful Improvements in Registering Bevels, of which the following is a specification.

The present invention relates to improvements in registering bevels and the principal object is to provide an instrument of the character described which is constructed of relatively few parts, simple of adjustment for operation and which may be manufactured economically.

A further object is to provide a device having no intricate or protruding parts and which may be folded and slipped into the pocket when not in use.

With these and other objects in view, the invention consists in the construction, combination and arrangements of parts as will be hereinafter described, illustrated in the accompanying drawings, and pointed out in the claims hereunto appended.

Figure 1 is a front elevational view of the improved bevel in open position.

Fig. 2 is a top edge plan view of the bevel in folded position.

Fig. 3 is a section on line 3—3 of Fig. 2. Referring to the drawings like numerals designate like parts in the various drawings.

The improved bevel is formed of three metallic sections, the numeral 5 designating the handle, while 6 and 7 designate the measuring sections. The section 6 is connected to the handle 5 by a pin having its opposite ends upset as at 9. A washer 10 is mounted on the pin 8 between the connected ends of the handle 5 and the section 6 and serves to hold the two in proper spaced relation.

The measuring section 7 is formed with a centrally disposed slot 10^x extending almost its entire length and terminating in a circular opening in its lower end, through which projects a screw 11. This screw 11 is formed with an enlarged head 12 and extension 13, which latter seats in an opening in the opposite end of the handle 5.

An adjusting nut 14 has a knurled edge portion and an extension 15 which seats within the circular opening 18 in the side of the member 5, upon opposite sides of the entrance to which are the points 22 and 23.

The section 7 at its outer end is cut on a bevel or obliquely to the longitudinal edges as at 16, while its opposite end is formed with a relatively narrow extension 17 extending in alignment with the inner edge of said section.

Screw 11 forms the pivot of rule section 7 upon the handle 5 and likewise when the rule 7, is to be adjusted, the screw 11 is loosened by turning the nut 14, which latter will release the extension 15 from the circular opening in the slot end.

Section 6 is formed on one side with degree indications 10 to 65 inclusive and outer degree indications 115 to 170, while the section 7 adjacent its end is provided with degree indications 70 to 90 and 90 to 110.

When it is desired to use the instrument as an ordinary bevel, the screw 11 is loosened to allow the scale section 7 to be turned on it as a pivot until the desired angle of the blade 7 relatively to the handle 5 is obtained as seen in Fig. 1 and then the blade 7 is clamped tightly in position by tightening up on the nut 14 as illustrated in Fig. 3.

To obtain angles say, from 10° to 65° between the handle 5 and the slotted section 7 the point 19 of section 7 is slid along the line 20 until it touches the one of the desired graduations just above the line, after which the nut 14 is tightened to hold the section 7 in adjusted position. The screw 11 may be loosened and the blade 7 moved endwise, the slot 10^x allowing of this movement, and the blade moved until the point 19 is brought to the desired graduation on the member 6 and the nut 12 then tightened.

The angle is indicated with reference to the member 17 and the bottom edge of the member 5, as will be evident from Figure 1.

When it is desired to obtain angles from 65° to 90°, the section 6 is adjusted to move the pin 21 along the inner edge of the slidable section 7, until the appropriate one of the points 22 or 23 registers with the graduations desired upon the inner edge of section 7.

Obtuse angles are obtained by using the angulation indicated by 135° in Fig. 1, the point 19 of section 7, designating the degree upon the upper part of section 6.

Likewise means are provided for measuring small angles particularly useful for tool setting, finding clearance angles etc. The tail extension 17 of section 7 being only $\frac{1}{8}$

inch wide gives greater clearance and enables smaller angles to be measured. This angle is the same as that between the handle 5 and section 6 and is denoted by the graduation 5 directly on line 20.

The instrument may be folded together by first pushing down upon section 6 and the opening 18 will span the screw 11 of the handle 5. Then the section 7 is adjusted 10 so that it is entirely enclosed between the handle 5 and section 6 after which the nut 14 is tightened to hold the part firmly together.

From the foregoing it is thought that the 15 construction of my invention will be clearly understood, and therefore, a more extended explanation has been omitted.

What I claim as new is:

1. A device of the character described, 20 comprising a handle, a longitudinally slotted section pivotally mounted on the handle, a pivot for said slotted section disposed in said slot, and a scale section pivoted on the handle and entirely disconnected from the slotted section, the slotted section slidably mounted on said handle, said sections having 25 scale graduations thereon, said slotted pivoted section adapted for cooperation with the other of said sections to determine angles of different degree and said sections being in the plane of the handle.

2. A device of the character described,

comprising a handle, a longitudinally slotted section pivotally mounted on the handle, a pivot for said slotted section disposed in 35 said slot, a scale section pivoted on the handle and entirely disconnected from the slotted section, the slotted section slidably mounted on said handle, said sections having scale graduations thereon, said slotted 40 pivoted section adapted for cooperation with the other of said sections to determine angles of different degree and said sections being in the plane of the handle, and means for holding said sections in adjusted 45 positions with respect to said handle.

3. An instrument of the character described, comprising a handle, a longitudinally slotted section pivotally mounted on 50 said handle, the pivot of said section being disposed in said slot, a scale section pivoted on the handle and entirely disconnected from the slotted section, the slotted section slidably connected to said handle, said sections having scale indications thereon, means for 55 connecting said slidable section to said handle, and means for determining different angulations.

In testimony whereof I affix my signature in the presence of two witnesses.

MICHAEL MULLARKEY.
